UNITED STATES PATENT OFFICE.

JOHANNES RUTHS, OF DJURSHOLM, SWEDEN, ASSIGNOR TO AKTIEBOLAGET VAPOR-ACKUMULATOR, OF STOCKHOLM, SWEDEN, A CORPORATION.

SUPPORT.

Application filed October 24, 1923, Serial No. 670,540, and in Sweden October 25, 1922.

My invention relates to supports for structures having relative movement of parts and aims to provide novel means for supporting such structures to give free movement in a number of directions and to take care of such conditions as expansion and contraction.

My invention is illustrated in the accompanying drawing in which Figure 1 shows diagrammatically a cylindrical structure with a manner of placing the supports. Figure 2 is a section on line 2—2, Figure 1; Figure 3 is a section on line 3—3, Figure 1; Figure 4 shows a different arrangement of supports; Figure 5 shows a modified construction of movable support; Figure 6 shows a modified construction of bracket support; and Fig. 7 shows one embodiment of a supporting part.

Reference character *a* designates the structure to be supported which may, for example, be a cylindrical steam storér with hemi-spherical ends subject to varying temperature and expansion and contraction in marked degree. The storér is supported by a fixed support *b* on one side, by movable supports *d* on the same side and by movable supports *c* and *e* on the opposite side. The fixed support *b* may be of any desired construction. It is shown (Figure 2) as a section of I beam *g* mounted on foundation *h* and secured to bracket 10. Support *c* which is transversely opposite support *b* is made of two parts *g* and 11, between which are arranged rollers 12 permitting movement as shown by the arrow heads, the rollers being arranged with their axes extending longitudinally of the cylindrical structure *a*. Support *d* (Figure 3) which is arranged longitudinally with respect to support *b* and the structure *a* comprises two parts like support *c* with rollers between them but with the rollers arranged at right angles to those of support *c*, that is with their axes transversely to the cylindrical structure so as to permit longitudinal expansion and contraction of the structure. Support *e*, placed diagonally from fixed support *b* with respect to the structure *a*, is formed with two parts with a vertical pin arranged between them, arranged to permit expansion and contraction of structure *a* in both transverse and longitudinal direction.

One manner of making support *e* is shown in Figure 7. It comprises a vertical pin

having somewhat rounded ends. The ends rest in sockets 16 and 17. It may be said that the pin swings about the lower stationary member in which socket 17 is formed as a pivot. It is a sort of pendulum though adapted to swing in all directions about its pivot. By properly forming the ends of the pin with respect to the socket surfaces or the various surfaces with respect to each other, the arrangement can be made such that, while movement in any horizontal direction is permitted, there is no rise or fall of the supported member in its movement.

Brackets 10 are riveted to the storér and are made to embrace a portion of the circumference of the storér, symmetrically or nearly so about the horizontal diameter of the storér, the brackets being arranged with seats 14 for support arranged somewhat outside the cylinder so that the supporting pressure is exerted somewhat outside the storér and in the extension of the horizontal diameter thereof. By this arrangement, the reaction forces give rise to a moment tending to counteract the distortion which is apt to be produced by shearing stresses and reaction forces.

Any number of supports *d* and *e* may be used as indicated in Figure 1.

Figure 4 shows a modification wherein supports *b* and *c* are placed at one end of the structure *a*. Any number of different arrangements are obviously possible.

Figure 5 shows a modification of support *e* wherein two sets of rollers *i* with their axes at right angles have a plate *j* between them and are arranged between foundation *h* and seat 14. This form also permits movement in all directions.

Figure 6 shows a modified form of bracket 10 comprising an angle section *h*, an intermediate plate *m* and a plate *l* fitted to the surface of cylindrical structure *a*.

Various modifications are possible within the spirit and scope of the invention wherefor it is not to be limited to the forms shown.

I claim:

1. Supporting means for a structure comprising a fixed support, a second support spaced from the fixed support and comprising a part adapted to be attached to the structure and means to permit said part to move toward or away from the fixed support, a third support spaced from the fixed

105

110

support in a direction at an angle to that at which the second support is spaced from the fixed support and comprising a part adapted to be attached to the structure and means to 5 permit the last-mentioned part to move toward or away from the fixed support and a fourth support spaced at an angle from the fixed support with respect to the second and third supports and comprising a part adapted 10 to be attached to said structure and having movement in all directions with respect to said fixed support.

2. Supporting means for a structure extending in longitudinal and transverse direction comprising a fixed support adjacent one side of the structure, a movable support on the same side of the structure permitting longitudinal movement of the structure, a second movable support on the opposite side 20 of the structure transversely opposite to said fixed support permitting transverse movement of the structure and a fourth support arranged longitudinally of the second support and permitting movement of the structure both longitudinally and transversely. 25

3. Supporting means for a structure extending in longitudinal and transverse direction comprising a fixed support adjacent one side of the structure, a second support on the 30 same side of the structure comprising two parts with rolling members between them to permit longitudinal movement of the structure, a third support comprising two parts with rolling members between them and situated on the opposite side of the structure transversely opposite the fixed support to permit transverse movement of the structure and a fourth support arranged longitudinally of the third support and comprising two 35 parts with a vertical pin between them, said pin being arranged to permit movement of said structure both longitudinally and transversely.

4. Supporting means for a structure comprising a fixed support, movable supports and a support comprising two parts adapted to have relative movement and a vertically arranged pin extending between said parts and in contact with said parts so that the pin 40 may swing about the one part in any direction.

5. Supporting means for a structure having longitudinal and transverse extension

comprising a fixed support on one side of the structure, a second support on the same 55 side of the structure comprising two parts and transversely placed rollers between the parts, a third support on the opposite side of the structure comprising two parts with longitudinally arranged rollers between the 60 parts, and a fourth support comprising two parts and a movable vertical pin between said parts.

6. Mounting means for a horizontal cylindrical structure comprising strengthening 65 members extending about a part of the circumference of the cylindrical structure substantially symmetrically about the horizontal diameter of the cylinder, seats on said members arranged outside the outermost 70 part of the cylinder and supporting means on which said seats rest, said supporting means comprising a fixed support adjacent one side of the structure, a movable support on the same side of the structure permitting 75 longitudinal movement of the structure, a second movable support on the opposite side of the structure transversely opposite to said fixed support permitting transverse movement of the structure and a fourth support 80 arranged longitudinally of the second support and permitting movement of the structure both longitudinally and transversely.

7. Supporting means for a structure extending in longitudinal and transverse direction comprising a fixed support adjacent one side of the structure, a plurality of additional supports on the same side of the structure, each comprising two parts with rolling members between them to permit longitudinal 90 expansion of the structure, a transverse movement support comprising two parts with rolling members between them and situated on the opposite side of the structure transversely opposite the fixed support to 95 permit transverse movement of the structure and a plurality of additional supports arranged longitudinally of the said transverse movement support, each of the last mentioned plurality of supports comprising 100 two parts with a vertical pin between them, said pin being arranged to permit movement of said structure both longitudinally and transversely.

In testimony whereof I affix my signature.
JOHANNES RUTHS.
